DESIGN FOR AN ELECTRIC FAN CASING

John G. Macdonald, Toronto, Ontario, Canada

Application September 17, 1936, Serial No. 64,904

Term of patent 14 years

To all whom it may concern:

Be it known that I, John G. Macdonald, a subject of the King of Great Britain and resident of the city of Toronto, county of York, Province of Ontario, in the Dominion of Canada, have invented a new, original, and ornamental Design for an Electric Fan Casing, of which the following is a specification, reference being had to the accompanying drawing, forming part thereof.

The figure is a perspective view of an electric fan casing showing my new design.

I claim:

The ornamental design for an electric fan casing, as shown.

JOHN G. MACDONALD.
